UNITED STATES PATENT OFFICE.

ALPHONZO R. BOWERS, OF SAN FRANCISCO, CALIFORNIA.

EXCAVATOR.

SPECIFICATION forming part of Letters Patent No. 372,956, dated November 8, 1887.

Original application filed December 9, 1876, and renewed April 16, 1879. Divided and this application filed July 16, 1887. Serial No. 244,542. (No model.)

To all whom it may concern:

Be it known that I, ALPHONZO B. BOWERS, of San Francisco, California, civil engineer, have invented an Improvement in Excavators, 5 of which this is a description.

This is a ninth division of the application filed December 9, 1876, and renewed April 16, 1879, being illustrated in part in original Figures 1 to 9, inclusive, 21, 22, and 23, and described on pages 3, 4, and 7 of the original specification.

It consists of a rotary excavator constructed to work with a side feed and either outward or inward delivery, in combination with any 15 suitable device for removing the spoil, said excavator being provided with peripheral spirally-arranged edges or blades having a drawing cut, with devices by which these edges or blades are braced and bound together, and 20 with excavating-edges on its outer end inclined backward from the direction of rotation to avoid hooking against obstructions and to give to these edges a drawing cut.

Figure 1 is a plan showing one form of this 25 excavator in combination with a suitable device for receiving and withdrawing the spoil. Fig. 2 shows the end cutting-edges and lower ring of the excavator. Fig. 3 shows a cross-section through the excavator, through an inner section of suction-pipe sometimes used, and through the excavator-shaft R. Fig. 4 is 30 a plan of the lower end of said suction-pipe and of a portion of said shaft.

C may be any of the well-known devices 35 suitable for removing the spoil from either inside or outside of the excavator. As here shown, it is a suction-pipe arranged to take its spoil from the inside, although it may be arranged to take it from the outside also, as 40 described and claimed in the eighth division of the original application. Its lower end, T, in the device shown, extends into the hollow excavator E, to support the bearing R' of the shaft R, and is enlarged and cut away on one 45 side to form an opening, G, for receiving the spoil. The excavator and device for removing the spoil, when used for dredging, is usually supported by a swinging ladder suspended from a derrick or crane by a chain attached to the eye c, or to a ring passing around 50 the suction-pipe at this point, the chains that

give the side feed being also attached to said ring or to the eyes c' c''.

E, as here shown, is a hollow rotary excavator identical with that described and claimed 55 in Letters Patent No. 318,859, issued to me May 26, 1885, except that in the present instance all its excavating-edges are constructed and arranged to make a drawing cut, and, like said excavator, some or all of its several parts 60 may be made separate and detachable, or the whole may be cast in a single piece.

The vanes k may consist simply of spiral cutting-blades, of suitable form and strength, cast with or secured in any suitable manner 65 to a hub, R², in the outer end of the excavator (by which rotation is communicated by any suitable power through the shaft R) and to one or more circumferential ring or rings, by which they are braced and bound together, though, 70 when the excavator is cast, it is better to provide these vanes with detachable steel knives S, extending from ring to ring or from end to end of the excavator, according to the preference of the user or builder. The cutting-edges 75 S and S' are set at an angle to give a free clearance and suitable lead.

The stiffening, bracing, binding rings t are 80 preferably, though not necessarily, made with beveled cutting-edges projecting outward beyond the spiral blades, the more easily to subdivide the spoil, and to serve as fenders to enable these blades to ride over and prevent them from catching against obstructions, and the ring b, on the inner end of the excavator, when used 85 with a central suction-pipe, is preferably extended inward to or near said pipe, where it may be provided with a strong flange to serve as a bearing or hub to run on said pipe, as shown.

I confine myself to neither an inward nor an 90 outward delivery, nor to the devices or form of construction shown; but, in this ninth division of the original application, I claim—

1. In combination, a rotary excavator 95 constructed and arranged to work with a side feed, provided with excavating edges or blades running spirally along its periphery, a device for bracing and binding said edges or blades together, and a device for removing the spoil. 100

2. In combination, a rotary excavator provided with excavating edges or blades running

spirally along its periphery, a stiffening-ring or stiffening-rings, to which said blades are secured and by which they are braced and bound together, and a suction-pipe for removing the spoil.

3. In combination, a rotary excavator having peripheral excavating devices spirally arranged, and fenders to prevent the cutting-edges of said devices from catching against obstructions.

4. In combination, a rotary excavator having peripheral excavating devices spirally arranged, fenders to prevent the cutting-edges of said devices from catching against obstructions, and a device for removing the spoil.

5. In combination, a rotary excavator having peripheral excavating devices spirally arranged, fenders to prevent said devices from catching against obstructions, and a suction-pipe for removing the spoil.

6. In combination, a rotary excavator having peripheral excavating edges or blades spirally arranged, a device for slicing or dividing the spoil delivered by said edges or blades, and a device for removing said spoil.

7. In combination, a rotary excavator having peripheral excavating edges or blades spirally arranged, a device for slicing and dividing the spoil delivered by said edges or blades, and a suction-pipe for removing said spoil.

8. In combination, a rotary excavator provided with excavating devices having a drawing cut, and fenders to prevent said devices from catching against obstructions.

9. In combination, a rotary excavator provided with excavating devices having a drawing cut, fenders to prevent said devices from catching against obstructions, and a device for removing the spoil.

10. In combination, a rotary excavator provided with excavating devices having a drawing cut, fenders to prevent said devices from catching against obstructions, and a suction-pipe for removing the spoil.

11. In combination, a hollow rotary excavator provided with excavating devices having a drawing cut and inward delivery between said devices to the interior of said excavator, a shaft for actuating said excavator, and a device for removing the spoil.

12. A hollow rotary excavator with inward

delivery and constructed to operate with a side feed and provided with excavating devices having a drawing cut, a shaft for actuating said excavator, and a suction-pipe for removing the spoil.

13. In combination, a rotary excavator consisting of peripheral excavating devices spirally arranged, braced, and tied together by a circumferential ring or by circumferential rings, and firmly connected to a hub in the end of said excavator, an actuating-shaft secured to said hub, a bearing for said shaft in the interior of said excavator, and a suction-pipe opening into said interior for removing the spoil.

14. In combination, a rotary excavator consisting of peripheral excavating devices spirally arranged, braced, and tied together and secured to a hub in the end of said excavator, excavating edges or blades on the end of said excavator inclined backward from the direction of rotation, an actuating-shaft secured to the hub and provided with a bearing in the interior of said excavator, and a suction-pipe opening into said interior.

15. In combination, a rotary excavator constructed and arranged to work with a side feed, provided with excavating edges or blades running spirally along its periphery and delivering their spoil to the interior of said excavator, and a device for removing said spoil.

16. In combination, a hollow rotary excavator provided with excavating edges or blades running spirally along its periphery and delivering their spoil to the interior of said excavator, and a suction-pipe opening into said interior.

17. In combination, a hollow cylindrical rotary excavator having excavating edges or blades running spirally along its periphery and delivering their spoil to the interior of said excavator, and a suction-pipe opening into said interior.

18. The hollow rotary excavator E, substantially as and for the purpose described, in combination with a device for rotating the same.
